FOOTWEAR.

Application filed March 15, 1928. Serial No. 261,995.

This invention relates to improvements in footwear and is directed more particularly to the provision of means for shaping the uppers at the heel portion of a shoe so that 5 it will conform to and snugly embrace the heel of the wearer to prevent slipping.

As is well known, the plies of material comprising the upper of a shoe have incorporated at the heel portion thereof a relatively 10 stiff member called a counter, the function of which is to stiffen and hold the sides of the upper in an upright position and to prevent its spreading or otherwise becoming out of shape. The counter merely supports the 15 sides of the upper so as to stiffen the structure, and gives to the heel portion its general shape only.

It has been attempted to shape the counter and consequently the upper at the heel so 20 that they will fit snugly and embrace the heels of the wearer; but the shape and size of heels of persons who may wear the same size shoe varies within wide limits so that in the majority of cases the shoes slip at 25 the heel.

In an attempt to overcome this slipping, anti-slipping pads of rubber, fabric or the like have been affixed to the inner liner of the heel of the shoe to fill up the space between the sides of the heel and shoe. These 30 are far from being satisfactory because they wear the heel of the stocking, lose their anti-slipping characteristics, do not stay in place and soon deteriorate. At best these 35 so-called "fillers" or anti-slipping devices are nothing more or less than a means of filling up the space and they are not intended to, and do not in any way, cause the shoe upper to properly embrace the heel of the foot, which obviously is the desirable way of preventing slipping. As a practical matter, 40 these "fillers" tend to cause the heel portion of the shoe to bulge in many cases.

As distinguished from the stiffening counter and "fillers" referred to, according 45 to one novel feature of our invention we provide means in the nature of a former which is adapted to cause the upper at the heel portion of a shoe to bear against and conform to the shape of the heel so as to 50 snugly embrace the heel and thereby obviate slipping of the shoe on the heel of the wearer.

According to another novel feature of the invention, we provide means for the purpose 55 described which may be incorporated in the

shoe at the time of manufacture so that it becomes a part of the shoe structure and cooperates therewith to provide a shoe which will fit the foot in the desired manner.

The novel features of the invention are 60 adapted for broad application but will in the form at present preferred be described in connection with a so-called "low" shoe, it being understood that the invention may be changed or modified to adapt it for use in 65 connection with other forms of foot wear.

In the drawings:

Fig. 1 is a side elevational view of a low shoe having incorporated therein the novel 70 features of the invention;

Fig. 2 is a perspective detail view of the former constituting part of the invention;

Fig. 3 is a similar view of a modified form 75 of the invention; and

Fig. 4 is a sectional elevational view taken on the line 4—4 of Fig. 1.

Referring to the drawings in detail, the invention will now be described.

A shoe is represented at S which has the usual sole 1, heel 2 and upper 3, the latter 80 being formed in the ordinary manner to have a heel embracing portion indicated at 4.

It is customary to provide a stiffening member such as a counter C indicated by dotted lines for holding or supporting the 85 upper which, as in the case shown, terminates at a point below the upper edge of the upper. The upper usually comprises outer and inner plies of material which enclose the counter so that the walls of the shoe or upper 90 above the counter, as at 6, are pliable and free to bend or flex. The upper does not, in the ordinary case, snugly embrace the heel. If made to properly embrace or fit heels of one size and shape, the walls obviously would 95 not fit heels of another size and shape equally well. To cause the heel portion of the upper to press against and snugly embrace heels of different sizes and shapes within a wide range, we provide a yieldable or resilient 100 spring-like former member M which is preferably incorporated in the shoe structure.

The former M may take various forms according to the type or style of shoe, and may be made of various materials such as wire, 105 bone, celluloid or the like, depending upon the type of shoe with which it is used.

According to the preferred form of the invention, the former M will take the form 110 of a pair of spring-like members m which

are pivoted together as at 7 so as to permit a relative movement thereof. These may be held in place by being embraced in some manner between the outer ply and the inner ply or liner of the upper of the shoe. It is usual to turn the upper edge of the outer ply inwardly into overlapping relation with the liner and the plies are usually secured together as by stitching indicated at 8. In such a case, the former member M may be enclosed by the overlapped edge of the outer ply, as shown in Fig. 4. The members will preferably be held by the upper so that they may move slightly relative thereto, whereby they will be free to bend or flex and will not be restricted in their bending movements by the material of the upper of the shoe. That is to say, the members should be free to slide back and forth to some extent with respect to the upper of the shoe to enable them to be bent as may be desired without wrinkling the material of the upper; as they would be in case they were fixed securely to the shoe upper.

25 With the former incorporated in the shoe, after the manner described, the upper portions 6 of the upper at the heel may be engaged by the fingers so that the former members may be shaped to the contour or shape of the sides of the heel and so as to press towards one another. When the former is thus bent to the shape desired, the heel portion of the upper will be yieldingly pressed thereby against the sides of the heel.

30 The former will hold the upper against or cause it to snugly embrace the heel so that the tendency of the shoe to slip at the heel is obviated.

35 In lieu of the articulated former members shown, it may be desired to provide a former M' of one piece, according to the modification of the invention shown in Fig. 3. This former may be secured to the upper of the shoe in such a manner that it is free to move slightly relative thereto to facilitate the bending thereof and will function as in the former case to cause the upper to snugly embrace the sides of the heel. In some

cases it may be desirable to provide a substantially wide, flat, spring-like former in 50 preference to the wire former shown and will depend, of course, upon the style of shoe and on the material of which it is made.

55 In any event, the former, as distinguished from a stiffener, will be bendable so that it may be bent to the contour of the sides of the heel and yieldable so as to cause the flexible portion of the upper to yieldingly embrace the heel. Thus the upper is not only shaped to fit the heel, but is pressed thereagainst to obviate the slipping tendency.

60 The form of the invention shown may be modified or changed to adapt the invention for various styles of shoes without departing from the spirit and scope of the invention; and we prefer therefore to be limited by the appended claim rather than by the foregoing description.

65 What we claim is:

70 A shoe comprising in combination, a substantially rigid counter at the heel thereof for stiffening the shoe at the sides and back of the heel of the wearer, plies of relatively pliable material at opposite sides of the counter in the form of an inner liner and an outer upper extending above said counter to provide pliable side and rear portions above said rigid counter which are adapted to be pressed against the heel of the wearer at the sides and rear thereof at points above 75 said counter, and a spring-like former of yieldable wire associated with the pliable portions of said liner and upper above said counter which includes side members disposed in said pliable side portions and connected together at the rear of the pliable portions for relative movements to press the pliable side portions against the heel of the wearer, the said former being held by the upper so as to be movable with respect thereto to permit a relative movement of the side members thereof.

75 In testimony whereof we have affixed our signatures.
